UNITED STATES PATENT OFFICE

2,592,872

SEAT STRUCTURE FOR SCHOOL DESKS

Philip F. Douglas, Carman, Manitoba, Canada

Application March 20, 1950, Serial No. 150,587
In Canada March 24, 1949

1 Claim. (Cl. 155—87)

1

The invention relates to school desks and particularly to an improvement in the type of desk shown and described in my Canadian Patent Number 370,271, for School Desks dated the thirtieth day of November 1937, and said improvement is directed particularly to the mounting of the desk seat, with the object of providing an arrangement which will withstand hard usage to which the parts of the arrangement are subjected in every day use and in a structure that can be produced at relatively low cost, readily assembled and is not unsightly.

With the above object in view, the invention consists essentially in the arrangement and construction of parts hereinafter described, reference being had to the accompanying drawing in which:

Fig. 1 is a perspective view of part of a school desk and showing the seat mounting, the seat appearing in up or not in use position.

Fig. 2 is a view similar to Fig. 1 with the seat in down or used position.

Fig. 3 is a side view showing the seat mounting as a whole.

Fig. 4 is a vertical sectional view at 4—4 Fig. 3.

In the drawing like characters of reference indicate corresponding parts in the several figures.

The desk embodies similar side frames 1 and 2 of cast metal utilized to support the desk top, back rest and seat, the back rest 3 and seat 4 being herein shown. The frames terminate in front and rear legs 5 and 6 and are provided forwardly with integrally formed, upstanding, seat supporting arms 7, the structural details of which will be later described.

It will be observed that each skeleton side frame presents outstanding continuous flanges 8 to which the desk top and back rest can be readily bolted and said flanges also serve to reinforce the frames and give rigidity to the assembled structure.

The side frames are connected together by a relatively long bolt 9 in the same manner as shown in the patent hereinbefore referred to.

The arm 7, in each instance, is spaced forwardly from the upgoing back rest engaging portion of the frame to provide a clearance space 10 for the rear edge of the upturned seat and the flange 8 hereinbefore mentioned borders the arm and presents a horizontal portion 8' which is used as a stop for the seat in its down or in use position. Each arm is also supplied with an integrally formed, horizontally disposed bear-

2

ing sleeve 11 which is utilized to receive a pivot pin shortly referred to.

The seat 4, which is of the usual curved form for comfortable seating, has two similar vertically disposed brackets 12 secured thereto by countersunk bolts 13 and each bracket presents an outstanding horizontal flange 12' through which the latter bolts pass. The seat attached brackets are located immediately to the inner sides of the arms 7 so that in the down position of the seat, the flanges 12' of the brackets engage the flange portions 8' of the arms. The flange 12' is fashioned to follow the contour of the seat. Each bracket is formed with an outstanding, integral, horizontally disposed pivot pin 14 which is adapted to enter and become pivotally received in the bearing sleeve 11 of the adjacent side frame.

It will be obvious that the pivot pins can be readily entered in the bearing sleeves when the desk is being assembled and prior to fastening up the bolt 9. It will be also noted that the pivot pins are relatively large in diameter so that they give ample bearing area in the sleeves, which is important as desk seat bearings are subjected to very hard and rough usage.

I wish now to refer to Fig. 3 and to point out particularly that when the seat is down or in used position, as shown, I have the wear resisting metals of flanges 8' and 12' in contact and the points of contact well in advance of a vertical line passing centrally through the pivot pin 14 so that the load of a person seated on the seat in down position, is for the greater part supported by the flanges 12' and absorbed by the arms 7, thereby relieving the pivot pins 14 of considerable thrust.

The large bearing area given the pins 11 insures of long life and there is no part to work loose or cause trouble, such as would occur if nutted bolts were employed for pivoting purposes, as is common practice.

I might mention that this desk can be supplied with the combination ink well and pen and pencil holder as shown and described in the patent hereinbefore mentioned.

What I claim as my invention is:

In a school desk, interconnected, similar, skeleton side frames provided with opposed, forward, upstanding arms in the plane of and spaced forwardly from the bodies of the frames and having the upper ends of the arms terminating in horizontal, outstanding flanges and the bodies thereof provided with relatively large diameter, aligned bearing sleeves underlying the flanges,

a pair of similar brackets positioned to the inner sides of the arms and provided with integrally formed pivot pins rotatably received within the sleeves and with outstanding flanges engageable with the arm flanges and a seat secured to the flanges of the brackets.

PHILIP F. DOUGLAS.
